UNITED STATES PATENT OFFICE.

ERNEST TH. GENNERT, OF NEW YORK, N. Y.

APPARATUS FOR EXTRACTING OIL FROM OLEAGINOUS SEEDS.

SPECIFICATION forming part of Letters Patent No. 393,973, dated December 4, 1888.

Application filed October 14, 1887. Serial No. 262,346. (No model.)

To all whom it may concern:

Be it known that I, ERNEST TH. GENNERT, of the city, county, and State of New York, have invented certain new and useful Improvements in Apparatus for Extracting Oil from Oleaginous Seeds, of which the following is a specification.

This invention relates to an improved apparatus for extracting oil from cotton and other oleaginous seeds on the principle of diffusion, as contradistinguished from extracting the oil by macerating, heating, and pressing the seed; and the invention consists of an apparatus for extracting oil from oleaginous seeds, which comprises one or more diffusers having a perforated false bottom and a bottom opening closed by a valve which is intermittently opened by means of a float attached to the stem of the valve, according as the level of the extracting-liquid—such as benzine or other volatile hydrocarbon—rises or falls in the diffuser. The stem of the discharge-valve of the diffuser is surrounded by a fixed center tube, in the upper end of which the float is guided. The bottom opening of the diffuser is connected by a pipe with a receiver for the oil obtained by diffusion from the seed, said receiver being provided with an interior steam-coil, the heat of which vaporizes the solvent, said vapors being conducted by a vertical pipe to a condenser supported above the diffuser, from which the condensed solvent is conducted again to the diffuser. When a number of diffusers are arranged in battery, they are connected by pipes having suitable stop-cocks, so as to conduct the solvent from the lower part of one diffuser to the upper part of the next diffuser. The steam-coils of the receivers are connected by steam-pipes with the source of steam-supply, while the bottom parts of the receivers are connected by pipes to establish a uniform level of oil in all the receivers. A supply-pipe for the solvent is connected with the return-pipes leading from the condensers to the diffusers, and provided with suitable stop-cocks, so as to supply each diffuser independently from the others with the required quantity of the solvent when it is to be used individually and not in battery.

In the accompanying drawings, Figure 1

represents a side elevation and section of my improved apparatus for extracting oil from oleaginous seeds, showing two diffusers connected in battery, Fig. 2 is a horizontal section on line *x x*, Fig. 1. Fig. 3 is a detail vertical central section of the float for opening and closing the valve of the diffuser. Figs. 4 and 5 are respectively a vertical and horizontal section of the valve and valve-casing drawn on a larger scale, Fig. 5 being a section on line *x x*, Fig. 4; and Figs. 6 and 7 are a vertical central section and a plan of the interior of the condenser used in connection with my apparatus.

Similar letters of reference indicate corresponding parts.

Referring to the drawings, A represents the diffuser of my improved apparatus for extracting oil from cotton and other oleaginous seeds. The diffuser A is preferably made of cylindrical shape and provided at the upper part with a neck, *a*, said neck being closed by a cover, *A'*. The bottom of the diffuser A is provided with a central opening, *b*, which is closed by a valve, B, the stem *b'* of said valve extending through a hollow center tube, *b*², to the upper part of the diffuser A.

The valve B is surrounded by a valve-casing, *B'*, which is attached to the bottom of the diffuser A and provided with openings *b*³, through which the oil extracted by the solvent is drawn off when the valve is opened. The center tube, *b*², is secured into the upper part of the valve-casing *B'*, as shown clearly in Fig. 4.

The upper end of the stem *b'* is provided with a float, C, of conical shape, which is guided by a central tubular portion, *b*³, on the center tube, *b*². The float C is made conical for the purpose of facilitating the charging of the diffuser with seed, it serving at the same time as a distributor or spreader for the seed.

The center tube, *b*², serves not only for guiding the float C, but mainly for protecting the valve-stem *b'* against the pressure of the seed charged into the diffuser, whereby the reliable working of the valve B is produced. The center tube, *b*², being extended into the guide-tube *b*³ of the float, terminates above the highest level that the solvent can reach in the

diffuser, and prevents thereby the flowing of the solvent into the center tube and from the same through the valve-opening b , but compels all the solvent to pass through the seed 5 into the diffuser.

A false perforated bottom, A^2 , is arranged above the bottom of the diffuser A , and a man-hole, a' , and man-hole cover a^2 above said false bottom A^2 , as shown in Figs. 1 and 2; said 10 man-hole serving to remove the seed when the oil is extracted. Below the diffuser A is arranged a closed vessel, D , which serves as a receiver for the oil extracted by the solvent from the seed in the diffuser, the receiver D 15 being connected with the bottom opening, b , of the diffuser by a connecting-pipe, a^3 , having a stop-cock, a^4 . The solvent employed for extracting the oil from the seed is supplied by a main pipe, E , a branch pipe, e , having a 20 stop-cock, e' , and a pipe, e^2 , having a funnel-shaped upper end, e^3 , to the neck a of the diffuser A , the solvent entering the diffuser thereby at atmospheric pressure.

At the interior of the receiver D and near 25 the bottom of the same is arranged a steam-coil, D' , which serves to heat the body of oil in the receiver D and vaporize the benzine contained in the same. The benzine-vapors are conducted through a valved pipe, D^2 , to 30 the condenser F , which is supported on upright rods f , secured to sockets f' at the upper part of the diffuser A , the condenser being constructed in such a manner that the cooling-water is conducted, by means of water supply and discharge pipes, through the 35 same in a counter-current to the direction of the flow of the vapors.

The construction of the condenser is shown in detail in Figs. 6 and 7, it being composed, 40 preferably, of a cylindrical casing having a central opening, the top and bottom plates of the casing being tightly packed to the body of the same by interposed insulating-plates of asbestos or other suitable material. A partition-wall, f^2 , of spiral shape extends from the inner to the outer circumference of the casing, so as to form a channel of nearly-uniform width, in which a coiled pipe, F^2 , is arranged, the convolutions of which incline toward the 45 bottom, so as to give to the solvent condensed in the pipe a continuous downward flow to the discharge-opening at the bottom of the condenser, which is connected with the branch pipe e , and by the same returned to the diffuser A , as shown in Figs. 1 and 6.

The oil-receiver D is provided with a hand-hole and hand-hole cover, d , and with a glass-covered opening, d' , through which the level of the oil in the vessel D can be readily observed.

60 The entire apparatus is supported by strong curved feet, which are bolted at their upper ends to the outer wall of the receiver D , so as to allow the bottom of the receiver to be attached or detached without disturbing the upper part of the apparatus. The diffuser A is supported on the receiver D by extending the wall of the same and bolting it to the wall

of the diffuser, the extension-wall being provided with openings for the passage of the connecting-pipes, as shown in Fig. 1.

Each apparatus, composed of a diffuser, receiver, and condenser, is complete in itself, and can be worked alone for extracting the oil, in which case the diffuser is charged with seed and benzine or other solvent. When the level 70 of the solvent gradually arrives at the upper part of the diffuser, so as to reach the float, the same is raised, and thereby the bottom valve opened, so that the oil extracted from the seed, being of greater specific gravity than 75 the solvent, is dropped through the connecting-pipe into the receiver D . When by the repeated opening and closing of the bottom valve of the diffuser a sufficient quantity of oil is conveyed to the receiver D , steam is admitted into the coil in the same and the solvent vaporized and conducted to the condenser, where it is condensed and returned in liquid state to the diffuser. The apparatus is worked with the solvent first charged into the same, 80 the solvent being distilled over and over again from the receiver D to the condenser, and only small quantities of benzine added from time to time, so as to supply that which may be lost by leakage.

When larger quantities of cotton-seed have to be extracted, a single apparatus would not be sufficient. In this case a battery of two or more of the same, according to the quantity of cotton-seed to be treated, is arranged, the 85 different apparatuses being connected by valved pipes G , which extend from the bottom of the diffuser of one apparatus to the upper part of the diffuser of the next apparatus. The pipe G is also connected with the 90 upper part of the first diffuser in order to work from the right-hand diffuser to the left, and vice versa. The connecting-pipe G is provided with stop-cocks g at both sides of the vertical portion of the connecting-pipe, so 95 as to regulate the flow of the solvent from either diffuser to the other. When all the diffusers are thus arranged in battery, the stop-cocks a^4 in the pipes leading to the receivers D are closed and a sufficient quantity 100 of benzine is admitted through the supply-pipe to fill all the diffusers of the battery, the benzine entering first into the first diffuser, then through and from the same to the second diffuser, then to the third, and so on. 105 When all diffusers are filled, the supply of solvent is interrupted. The bottoms of the oil-receivers D are also connected with each other by a pipe, h , which is provided between two receivers with a stop-cock, so as to shut out 110 any receiver in case it should be necessary for repairs or for working each apparatus singly.

The connecting-pipe h serves for the purpose of establishing a uniform level of oil in 115 all the receivers. The steam-coils D' of the receivers are also connected with each other, so that the distillation of the solvent is going on in all the receivers at the same time. By

arranging a number of receivers and diffusers in battery in the manner described, and passing the solvent successively through the diffusers, the oil is extracted from the seed by 5 fractional diffusion, which is accomplished quicker than when the diffusers of the battery would be operated singly. The solvent takes up a proportionately large quantity of oil in the first diffuser, a smaller quantity in 10 the second, a still smaller in the third, and in the last diffuser the solvent carries a comparatively large quantity of oil, which requires but a short exposure to distillation for removing the solvent.

15 The benzine-pipe E is connected with all the return-pipes of the condensers, so that any diffuser can be recharged with benzine and seed while the adjoining diffusers are disconnected from the same. When all the diffusers 20 of the battery have been charged with seed and benzine and a sufficient quantity of oil collected in the receivers, the benzine remaining in the oil is distilled off by admitting the steam to the coils of the receivers, the benzine being then condensed and returned from the 25 condensers to the different diffusers, whereby a continuous supply of benzine through the seed in the same is kept up until the oil in the same is entirely extracted. The first diffuser is then cut out and the charge of seed 30 in the same removed through the side man-hole and a new charge of seed placed into the same. The diffuser is then connected again with the other diffusers and filled with benzine that has passed through the remaining 35 diffusers. The next diffuser is then cut out, recharged with seed, and resupplied with benzine that has passed through the other diffusers, and so on, so that the oil is extracted 40 from the seed continuously on the principle of fractional diffusion.

Having thus described my invention, I claim as new and desire to secure by Letters Patent—

45 1. The combination of a diffuser provided with a supply-pipe having a funnel-shaped end, a receiver below the same, a valved pipe connecting the diffuser with the receiver, a steam-coil in the receiver, a condenser above 50 the diffuser, a pipe connecting the receiver with the condenser, and a pipe leading from the condenser into the funnel of the supply-pipe, so as to supply the solvent to the diffuser at atmospheric pressure, substantially 55 as set forth.

60 2. The combination, with a diffuser having a bottom opening, of a valve for said opening, a float applied to the stem of the valve, a fixed guide-tube extending around the valve-stem and extending into the float, a receiver below 65 said diffuser, and a pipe connecting the bot-

tom opening of the diffuser with the receiver, substantially as set forth.

3. The combination of a diffuser having a bottom opening and a perforated false bottom, a valve for said opening, a float applied to the stem of the valve, a fixed guide-tube extending around the valve-stem and into said float, a receiver below the diffuser, a pipe for connecting the bottom opening of the diffuser with the receiver, a condenser above the diffuser, a valved pipe connecting the receiver with the condenser, and a return-pipe connecting the condenser with the upper part of the diffuser, substantially as set forth. 70

4. The combination of a diffuser having a valved bottom opening, a receiver below the diffuser, a pipe connecting the bottom opening with the receiver, a steam-coil in said receiver, a condenser having a spiral interior 80 wall, so as to form a spiral channel, a valved pipe connecting the receiver with the condenser, a spiral condensing-coil in the spiral channel of the condenser, water supply and discharge pipes for the condenser, and a 85 valved return-pipe connecting the condensing-coil with the diffuser, substantially as set forth.

5. A diffuser having a bottom opening, a valve for opening or closing said opening, a 90 float attached to the upper end of the stem of said valve and provided with an interior guide-tube, and a fixed guide-tube for the valve-stem and float, substantially as set forth.

6. A diffuser provided with a perforated 95 false bottom, a man-hole and cover above said bottom, a bottom opening, a valve for closing said opening, a float applied to the upper end of the valve-stem and having an interior guide-tube, and a central guide-tube for the 100 stem and float, substantially as set forth.

7. The combination of two or more diffusers having valved bottom openings, receivers below said diffusers, condensers above said diffusers, valved pipes for connecting the diffusers and receivers, the receivers and condensers, and the condensers and the upper parts of the diffusers, valved pipes connecting the bottom parts of the diffusers with the upper parts of the adjoining diffusers, valved 110 pipes connecting the bottoms of the receivers, and valved pipes for connecting the supply-pipes of the diffusers, substantially as set forth.

In testimony that I claim the foregoing as 115 my invention I have signed my name in presence of two subscribing witnesses.

ERNEST TH. GENNERT.
